VERNE WAYMAN MILLER, OF OMAHA, NEBRASKA, ASSIGNOR TO THE MONARCH TYPEWRITER COMPANY, OF SYRACUSE, NEW YORK, A CORPORATION OF NEW YORK.

TYPE-WRITING MACHINE.

1,012,143.

Specification of Letters Patent. Patented Dec. 19, 1911.

Application filed September 10, 1906. Serial No. 333,960.

To all whom it may concern:

Be it known that I, VERNE W. MILLER, citizen of the United States, and resident of Omaha, in the county of Douglas and State of Nebraska, have invented certain new and useful Improvements in Type-Writing Machines, of which the following is a specification.

My invention relates to typewriting machines and more particularly to indicating mechanism therefor.

When writing on index cards, filling in partly printed blanks and the like it has often been either desirable or necessary to resort to line spacing different from that provided for by the ordinary line spacing mechanism. It has been customary heretofore in such cases to throw the regular line spacing mechanism out of operation and to throw the so-called fractional line spacing mechanism into operation, thereby enabling the operator to move the platen any desired distance for line spacing and to effect a spacing not provided for by the regular line spacing mechanism. But in such cases it is necessary to rely on the eye or judgment of the operator to secure a uniform spacing between the lines.

One of the main objects of my invention is to overcome this disadvantage and to provide simple and efficient means to assist in securing a uniform spacing between lines under the conditions such as those pointed out above.

To the above and other ends which will hereinafter appear, my invention consists in the features of construction, arrangements of parts and combinations of devices to be described in the following specification and particularly pointed out in the appended claims.

In the accompanying drawings, wherein like reference characters indicate corresponding parts in the different views, Figure 1 is a central vertical sectional view of so much of the upper portion of a typewriting machine as is necessary to show my invention in its application thereto; the section being taken on the line $x-x$ of Fig. 2 and looking in the direction of the arrow

at said line. Fig. 2 is a fragmentary detail front elevation of one form of a device embodying my invention, a part of the machine on which it is mounted and a portion of the platen. Fig. 3 is an enlarged detail fragmentary plan view showing the left-hand end of the carriage and the parts carried thereby; this view disclosing so much of the step-by-step and fractional line spacing mechanism as is necessary for consideration in the present case. Fig. 4 is a detail front elevation of another form of device embodying my invention. Fig. 5 is a transverse sectional view of the same on an enlarged scale, the view being taken on the line $y-y$ of Fig. 4 and looking in the direction of the arrow at said line.

I have shown my invention applied to a Monarch "visible" or front-strike typewriting machine, but it should be understood that the invention is applicable to typewriting machines of a different character.

The corner posts 1 of the machine support a top plate 2 from which upwardly extending standards 3 project. The standards 3 have fixed guide rails 4 secured thereto by screws 5. The inner faces of the guide rails 4 are grooved at 6 to receive anti-friction balls 7 which likewise coöperate with grooved guide ways 8 that form part of a rear carriage bar 9. At each end of the bar 8 is a forwardly projecting arm 10 in which a platen shaft 11 is journaled, the platen shaft carrying a rotary platen 12. The cross bar 9 and end bars or arms 10 constitute a platen frame or carriage supported on the fixed guide rails 4 through the anti-friction balls 7 and adapted to travel from side to side of the machine. Forwardly extending spring arms 13 are secured to the carriage by screws 14 and support a scale plate designated as a whole by the reference numeral 15. The scale plate in the present instance is bent as represented in Fig. 2, and two scales 16, 17 are provided on the face thereof. A type bar segment 18 is arranged in any suitable manner to be shifted vertically to change the case position of the types and carries upwardly and rearwardly striking segmentally arranged

type bars 19 pivoted thereto at 20, the forward ends of said type bars resting on a pad 21 which is supported by arms 22 which project forwardly from the type bar segment. A link 23 is pivoted at 24 to each type bar and is connected at its rear end with the usual type bar actuating mechanism, such as that employed, for instance, in the Monarch machine. The mechanism thus far described constitutes parts of the Monarch typewriting machine, and the description thereof is sufficient to afford an understanding of my invention in its application thereto.

15 The combined card guide, indicating and pressure device and its supports are secured to a vertically disposed frame plate 25 attached to depending lugs 26 on the top plate of the machine by screws 27. A supporting bracket 28, formed at each side near its top with a forwardly turned ear 29, is attached to the frame plate 25 by shouldered screws 30. The ears 29 are perforated to receive a short rod 31 which is fixed in the bracket 28 and serves to pivotally support the pressure and indicating devices which are represented as a whole by the numeral 32 and will, for convenience, be generally referred to hereinafter as a pressure device or card guide. The card guide 32 is preferably formed of sheet metal in one piece and generally resembles in shape the capital letter H having a cross bar 33, two upwardly extending fingers 34 and two downwardly extending arms 35. Each of the upwardly extending fingers comprises a narrow resilient portion 36, the upper edge of each finger being elongated and provided with a horizontally disposed letter-space scale 37 divided according to the scales 16 and 17 or, in other words, the scale marks are a letter-space distance apart. The cross bar 33 is provided with an indicator or pointer 38 which is adapted to coöperate with the lower 45 or carriage scale on the scale bar 15 and the ends of the cross bar which project laterally somewhat beyond the arms 35 are bent rearwardly, forming tabs or ears 39 which are perforated to permit the free passage of the short rod 31 which serves to pivotally support the card guide. A wire spring 40 is coiled around the rod 31, one end of said spring abutting the bracket 28 and the other end pressing against the card 50 guide below the pivot 31, the arrangement being such that the spring tends to exert a constant pressure on the card guide so that the fingers 34 are pressed lightly against the front of the platen. A locking 55 plate 41 preferably formed of sheet metal and having forwardly turned or bent contact portions 42 is slidably and frictionally mounted on the bracket 28 below the card

guide proper, being secured to said bracket by the shouldered-screws 30. The locking plate is provided with slots 43 through which the shouldered-screws pass, the shouldered portion of said screws abutting the front face of the bracket 28 and the threaded portion of the screws passing clear through perforations in said bracket and in the frame plate 25. The card guide, it will be understood is carried by a fixed portion of the machine and is located centrally thereof, being pivoted on the rod 31 in such a way that 70 fingers 34, as they rest against the platen, have a slight forward inclination. When the locking plate 41 is in the lowermost position the pressure device or card guide is pressed against the platen by the force exerted by the spring 40, and serves to exert a gentle pressure for properly controlling ordinary paper or the like when it is fed through the machine in the usual manner. When it is desired to write on cards, envelopes, thick paper and the like the locking plate 41 is slid upwardly by means of finger pieces 44 to the position shown in Fig. 1. As the locking plate moves upwardly the contact portions 42 will engage cams 45 on the arms 35, camming said arms toward the operator and forcing the fingers 34 into positive engagement with the platen. The card device thus far generally described is somewhat similar to that employed in the 95 Monarch machine and fully described in the patent to George A. Seib, No. 831,382, dated May 22nd, 1906.

In accordance with my present invention the upper edge 46 of the left-hand finger 100 34 constitutes a line indicator that registers with the printing line indicated by the dotted line a, as in Fig. 2, and registers with the bottom of the characters printed by said line as shown in Fig. 2, whereas the arm 34, which is situated on the opposite side of the printing point indicated by the comma in Fig. 2, extends across the printing line and the upper edge 47 thereof constitutes a line indicator situated at a predetermined line space distance from the printing line. The distance between the parallel indicating edges 46 and 47 is determined by the character of the spacing desired between lines. If desired, the construction may be 105 made with the two arms 34 formed from one piece with the edges 46 and 47 situated the desired distance apart in accordance with the character of spacing desired or the arm at the right-hand side of the printing point 110 may be made in two pieces, as shown in Fig. 4, the member 34^a in this construction being adjustable on the member 36^a so that the indicating edge 47 may be adjusted relatively to the printing line indicator 46 to 115 120 provide for any character of spacing de-

sired. In this construction shown in Figs. 4 and 5 the arm or member 34^a is preferably struck up from a piece of sheet metal and is provided with clamping arms 48 which are bent around the edges of the member 36^a and frictionally hold the member 34^a in any position to which it may be moved on the member 36^a, a finger piece 49 projecting from the member 34^a to facilitate the vertical adjustment thereof. Otherwise the construction shown in Figs. 4 and 5 is similar to that illustrated in Figs. 1 and 2.

When writing on index cards, filling in partly printed blanks and the like, it is often desirable or necessary by reason of the spacing on the cards or blanks to resort to line spacing different from that provided for by the ordinary line spacing mechanism, which, in the present instance, comprises a line spacing ratchet wheel 50 forming part of a platen head at the left-hand end of the machine, as shown in Fig. 3, and a co-operating line spacing pawl 51 which is actuated by a finger piece 52 operatively connected with the line spacing pawl. I have shown in Fig. 3 the fractional line spacing mechanism employed in the Monarch machine which comprises a finger piece 53 connected to a sleeve 54 which carries at its inner end a disk 55. A detent roller 56 is carried by a spring 57 secured to the frame of the machine by a screw 58. This detent roller normally bears against the teeth of the line spacing ratchet wheel when the ordinary line spacing mechanism is in operation and a bearing for the pivot of the detent roller rests against the outer face of the disk 55 and is adapted to co-operate with a cam groove 59 in the outer face of the disk. By moving the finger piece 53 to the position shown in Fig. 3 the detent roller is cammed out of contact with the teeth of the line spacing ratchet wheel and the pressure of the spring 57 is exerted against the disk 55 which in turn bears against a friction washer 60 which is pressed against the end of the platen, constituting a friction means for affording a line spacing movement of the platen to any desired extent by either of the finger wheels 61 and which may be employed by the operator for irregular line spacing.

In the operation of the devices a card or work sheet *c* is inserted in the machine and fed forward in the usual manner. It may be assumed that this work sheet is not provided with lines and that it is desired to effect a line spacing thereof which does not correspond with the line spacing which can be effected by the ordinary line spacing mechanism, or that lines are ruled on the cards or work sheet, and that the distance between these lines does not correspond with

any line spacing which can be effected with the ordinary line spacing mechanism and that the distance between the indicators 46 and 47 corresponds to the spacing between lines which it is desired to secure. Then the finger piece 53 will be moved to the position shown in Fig. 3 so as to throw the ordinary line spacing mechanism out of operation. The platen is then turned until the proper portion of the work sheet where it is desired to begin the writing is brought into register with the printing line indicator 46 and the first line indicated by the dotted line *b* may be written. The operator then turns the platen until the printed line is brought into register with the line indicator 47 and proceeds to write the second line. After this line is completed the card or work sheet may be set for the third line of writing by merely turning the platen until the line indicator 47 is in register with the second written line. Then the operator may proceed to write the third line and so on indefinitely, the lines being properly spaced apart and the indicating mechanism assuring, with the mechanical accuracy, the proper spacing between lines, affording a neat appearance in the work produced and no reliance on the eye or judgment of the operator is necessary, except to see when the lines are in register with the indicators to secure proper spacing between lines.

In certain classes of card index work a line is written on a card and the card is removed until some future time when it is reintroduced into the machine and a second line is written just below and close to the first line. The card is then removed and at some future time it is again inserted in the machine and a third line is written and so on until the card is filled. Usually the lines are spaced closer together than is provided for by the regular line spacing mechanism. By my present invention this class of work can not only be more rapidly effected than heretofore but the spacing between the various lines on each card and the spacing on the various cards will be uniform, thus greatly enhancing the neatness in their appearance. The spacing between the two arms 34 is such that it constitutes in effect a printing point indicator, the printing point, as heretofore stated, being represented by the comma in Fig. 2 and the scale 37 indicating the letter space positions along the line of print. The parallel line indicators 46 and 47 may be properly spaced apart by forming the edge of the indicator 47 in the first instance at the proper distance from the line indicator 46 when the same character of spacing is to be provided for all the work to be produced. However, I prefer to employ an adjustable line indicator 47 of

the character shown in Figs. 4 and 5 in order that the indicator 47 may be adjusted according to any character of spacing which it may be desired to effect. The indicating devices are also especially convenient in making corrections and alterations, and from certain aspects of my invention the indicating devices may be considered apart from the paper guiding and feeding devices and regarded solely as indicating means, whereas from certain other aspects the indicating devices may be regarded as parts of the card guide or paper feeding devices.

It will be understood that by reason of the fact that the arm which carries the indicator 47 crosses the printing line the cards or work sheets will be efficiently pressed against the platen at the printing line and will be efficiently directed to the usual paper fingers 61.

When I refer in the accompanying claims to a "fixed" indicator I mean an indicator which is carried by a fixed portion of the machine as distinguished from one that is carried by and travels with the carriage.

What I claim as new and desire to secure by Letters Patent, is:—

1. In a typewriting machine, the combination of a line space indicator having indicating means registering with the printing line and having indicating means situated a line space distance from said printing line, and means for effecting a relative adjustment between said indicating means.

2. In a typewriting machine, the combination of a line space indicator carried by a fixed portion of the machine and having indicating means registering with the printing line and also having indicating means situated a line space distance from the printing line, and means for effecting a relative adjustment between said indicating means.

3. In a front strike typewriting machine, the combination of a carriage, a platen carried thereby, indicating means fixed against movement with the carriage and arranged adjacent to the printing point and coöperative with the paper to indicate both letter and line space distances.

4. In a typewriting machine, the combination of an indicator having two parallel indicating edges, one of said edges registering with the printing line, and means for affording a relative adjustment between said indicating edges.

5. In a typewriting machine, the combination of a platen, an indicator coöperating with the platen or the paper thereon and carried by a fixed portion of the machine and having parallel indicating edges, one of said edges registering with the printing line, and means for affording an adjustment between said indicating edges.

6. In a typewriting machine, the combination of two relatively adjustable line indicators carried by a fixed portion of the machine, one arranged on each side of the printing point. 65

7. In a typewriting machine, the combination of two relatively adjustable line indicators carried by a fixed portion of the machine, one arranged on each side of the printing point and each of said line indicators having a letter spacing scale. 70

8. In a typewriting machine, the combination of a platen, and two relatively adjustable line indicators which are carried by a fixed portion of the machine and coöperate with the platen at each side of and adjacent to the printing point. 75

9. In a typewriting machine, the combination of a platen, a printing line indicator that coöperates with the platen and registers with the printing line, a second line indicator that coöperates with the platen 85 and extends across the printing line and indicates a line position at a predetermined distance from the printing line, and means for effecting an adjustment between said indicators. 90

10. In a visible typewriting machine, the combination of a platen, and a combined printing point and printing line indicator carried by a fixed portion of the machine and spring pressed toward the platen, said 95 indicator having indicating means normally in register with the printing line and situated at the left of and adjacent to the printing point, and also having indicating means situated to the right of and adjacent to the 100 printing point and crossing the printing line, said last mentioned means indicating a line position adjacent to the printing line, and means for effecting a relative adjustment between said indicating means situated 105 to the right and left of the printing point.

11. In a typewriting machine, the combination of a platen, a card guide coöperating therewith, said guide having a printing line indicator and an indicator that is adapted 110 to register with a previously written line when the line indicator is in register with the printing line, and means for effecting a relative adjustment between said indicators.

12. In a front strike typewriting machine 115 in which the printing instrumentalities are adapted to swing upwardly and rearwardly and to strike against the front face of the platen, the combination with the platen, of a card guide carried by a fixed part of the 120 machine below the printing point, and extending upwardly therefrom and adapted to guide a card upwardly to the printing point, said guide comprising two upwardly extending arms, one longer than the other, 125 the shorter arm being arranged to the left

of and adjacent to the printing point and the upper edge thereof registering with the printing line and the longer arm extending up above the printing line on the right of 5 the printing point and adjacent thereto and terminating in an upper registering edge a line space distance from the printing line indicator, said arms coöperating with a card 10 on opposite sides of the printing point and one at and the other above the printing line,

and the types being adapted to print between said arms.

Signed at Omaha, in the county of Douglas, and State of Nebraska, this 25th day of August, A. D. 1906.
